UNITED STATES PATENT OFFICE.

JOHN B. GOUNDRY, OF BELLEVILLE, MICHIGAN, ASSIGNOR OF ONE-HALF
TO HOWARD I. POST AND FRANK W. NELTHORP, OF BELLEVILLE,
MICHIGAN.

FENCE-POST.

SPECIFICATION forming part of Letters Patent No. 758,591, dated April 26, 1904.

Application filed December 26, 1903. Serial No. 186,656. (No model.)

To all whom it may concern:

Be it known that I, JOHN B. GOUNDRY, a citizen of the United States, residing at Belleville, in the county of Wayne and State of Michigan, have invented new and useful Improvements in Fence-Posts, of which the following is a specification.

This invention relates to fence-posts, and especially to fence-posts formed of concrete, cement, artificial stone, or other suitable material which is molded while in a plastic state and is permitted to set, so that the post becomes solid and hard; and it has for its object to provide means for effectually strengthening the post, and the material from which the post is made will be securely held together should the post have a tendency to break or crack.

It has for its further object to combine with the strengthening means suitable fastening means for attaching the wires to the post.

To these ends my invention consists in the features and in the construction, combination, and arrangement of parts hereinafter described, and particularly pointed out in the claims following the description, reference being had to the accompanying drawings, forming a part of this specification, wherein—

Figure 1 is a perspective view, the post being shown in dotted lines. Fig. 2 is a vertical sectional view. Fig. 3 is a view in side elevation illustrating one of the posts and a portion of the fence, and Fig. 4 is a transverse horizontal sectional view.

Referring to the drawings, the numeral 1 indicates a fence-post which may be constructed of any plastic material suitable for the purpose—as, for example, concrete, cement, artificial stone, or the like—said post being of any suitable shape and dimensions, but is preferably made rectangular in cross-section, as shown, and slightly tapered from its lower to its upper end.

The numerals 2 and 3 indicate two strengthening-links, each composed of a single rod which is bent in the shape of an oblong link slightly narrower at its upper end than at its lower end, the ends of the rods, constituting the links, being welded together.

In making the post a suitable mold is provided, and the material while in a plastic state is filled into the mold, and the strengthening-links are embedded in the material while still in its plastic condition. As clearly shown in the drawings, the two links are arranged at right angles to each other, one link being inserted within the other and the two links crossing one another, one of said links lying in a vertical plane which is disposed at right angles to the vertical plane in which the other link lies, and the links are so arranged in the post that one of said links will lie in a vertical plane which passes transversely through the center of the post and the other link will lie in a corresponding vertical plane disposed at a right angle to the plane in which the first-named link is disposed. The material composing the post completely surrounds the links. The links may be conveniently embedded in the post during the course of manufacture of the latter in the following manner: A suitable box or trough like mold is provided, closed on its sides, bottom, and ends, but open at the top. This mold being laid in a horizontal position, a suitable amount of plastic material is then placed in the bottom of the mold to cover the latter, say, to a depth, for example, of one-half an inch. The link 2 is then arranged centrally in the mold, its lower side resting on the partial filling of material in the bottom of the mold and its two sides standing in a vertical plane. The mold is then filled up with the plastic material to approximately one-half its depth, when the other link 3 will be laid horizontally on the material and at a right angle to the link 2. The mold is now completely filled with the plastic material and the material allowed to set and become hard and solid. The finished post will possess great strength and will be enabled to resist the action of frost and the weather and will also sustain very heavy strains, and this result is furthered and aided owing to the manner of disposing the links within the body of the post—that is to say, by arranging them one within the other and in planes at right angles to each other—the arrangement being such that the links extend

- across the center of the post and not in the corners. By making the links endless they will resist all tendency of the links being drawn out of the post or any portions of the 5 post separating in case the post should be cracked or broken. Furthermore, owing to the rounded shape of the links all sharp corners are avoided which might have a tendency to crack the post.
- 10 For the purpose of providing efficient means for securing the wire-fence strands to the post I provide fastening devices each consisting of a suitable length of wire which is bent to form a loop 4, which surrounds both members of 15 one of the links, and after having been passed around the members of said link the ends are twisted, as at 5, close to the adjacent member of the link about which the tie or fastening passes. These ties or loops are passed around 20 the links and twisted in place before the links are embedded in the plastic material of which the post is formed, and the free ends of the ties of the loops project beyond one of the sides of the post. The wire strands 6, forming 25 the fence, are arranged between the free ends of the ties or loops 4, and said free ends are twisted, as at 7, about the wire-fence strands, and thus securely attach the latter in place to the posts. This not only forms a very 30 secure fastening for the fence-strands, but also provides a fastening which may be detached from any one or more of the strands at any time it may be desired for the purpose of repairing, changing, or altering the fence.
- 35 A fence-post constructed in the manner above described and as shown in the drawings is capable of being expeditiously manufactured at a relatively small cost and possesses great strength and the ability to withstand the action 40 of frost and the effects of atmospheric changes and the weather. It also enables a fence to

be put up very rapidly and without the necessity of employing skilled labor or special tools.

I do not wish to be understood as limiting 45 myself to the particular manner in which the fence-strands are secured to the posts, except as hereinafter specifically pointed out in the claims, as any suitable means for securing the fence-strands to the posts may be adopted. I 50 also wish it to be understood that I do not confine my invention to fence-posts alone, as it will be evident that the strengthening means may be employed in the construction of all kinds of artificial stonework. 55

Having described my invention, what I claim is—

1. A fence-post molded from plastic material and rectangular in cross-section, two endless links embedded longitudinally therein, one 60 of said links being wholly arranged within the other and said links being disposed in planes at right angles to one another and at right angles to the sides of the post, substantially as described. 65

2. A fence-post comprising a post molded from plastic material, two endless links embedded longitudinally therein, one of said links being wholly arranged within the other and said links being disposed in planes at right 70 angles to one another and to the sides of the post, and fastenings consisting of wire loops passing around both members of one of said links and twisted at their ends to embrace the fence, substantially as described. 75

In testimony whereof I have hereunto set my hand in presence of two subscribing witnesses.

JOHN B. GOUNDRY.
